(57) **CLAIM**

The ornamental design for bolt or nut tightening device, substantially as shown and described.

DESCRIPTION

FIG. 1 is a first perspective view of a bolt or nut tightening device of the present design, as seen from diagonally left upward;

FIG. 2 is a second perspective view thereof, as seen from diagonally right upward;

FIG. 3 is a front elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a sectional view taken on line 8—8 of FIG. 4 omitting internal mechanism of the device;

FIG. 9 is a sectional view taken on line 9—9 of FIG. 3

FIG. 10 is a sectional view taken on line 10—10 of FIG. 3

FIG. 11 is a sectional view taken on line 11—11 of FIG. 3

FIG. 12 is a sectional view taken on line 12—12 of FIG. 3

FIG. 13 is a sectional view taken on line 13—13 of FIG. 3; and,

FIG. 14 is a sectional view taken on line 14—14 of FIG. 3. The broken lines are shown in the views for illustrative purposes only and form no part of the claimed invention.
